UNITED STATES PATENT OFFICE.

LEWIS CREW FISHER, OF COLUMBUS, OHIO.

POST.

SPECIFICATION forming part of Letters Patent No. 727,335, dated May 5, 1903.

Application filed April 22, 1902. Serial No. 104,224. (No model.)

To all whom it may concern:

Be it known that I, LEWIS CREW FISHER, a citizen of the United States, residing at Columbus, in the county of Franklin and State 5 of Ohio, have invented a new and useful Post, of which the following is a specification.

My invention relates to improvements in posts in which iron pipe or tubing is used, with the auxiliaries hereinafter specified.

10 The object of the invention is to produce a post having a point provided with recesses for guiding the securing-points; furthermore, to provide a post with openings alining with the recesses of the lug.

15 Finally, an object of the invention is to provide an anchor-post which will possess advantages in points of simplicity, efficiency, and durability, proving at the same time comparatively inexpensive.

20 With the foregoing and other objects in view the invention consists in the details of construction and in the arrangement and combination of parts, to be hereinafter more fully set forth and claimed.

25 In describing the invention in detail reference will be had to the accompanying drawings, forming part of the specification, wherein like characters denote corresponding parts in the several views, and in which—

30 Figure 1 is a view in elevation, partly in section, illustrating a post, its anchoring means, and the application of the anchoring means. Fig. 2 is a detail view of the point or plug. Fig. 3 is a view in elevation of the 35 lower end of the point, the upper portion being sectioned on the line xx of Fig. 2. Fig. 4 is a view in elevation of the securing-prongs. Fig. 5 is a sectional view of the post and point.

40 In the drawings, A indicates the anchor-prongs, which are curved longitudinally and have their upper ends looped to embrace the link a . The point B has a shoulder b' , on

which the tubular post C is seated, said post being secured to the point by a pin b'' . The 45 point has its upper surface and edge provided with recesses b , inclined from the upper surface, terminating in line with the opening c of the tubular post.

In practice the anchoring-points are applied 50 in the recesses of the post-point and are pressed by the rammer D until the said points pass down the inclined surface of the recesses of the point, through the openings in the post, and into the ground. 55

The construction, operation, and advantages will, it is thought, be understood from the foregoing description, it being noted that various changes may be made in the proportions and details of construction without departing from the scope of the invention. 60

I am aware of the existence of a metal fence-post with a tapering point secured by split anchor-bars driven through apertures in the tubular part, also of a post secured by pins 65 driven from within.

I claim as new in my invention and desire to protect by Letters Patent—

In a device of the character described, a tube having a driving-point at its lower end, 70 said driving-point having inclined grooves cut in its upper portion forming guides and a shoulder formed at the base of the beveled aperture of the point, said tube having openings below the upper end of the point, coinciding with the inclined grooves, and curved 75 securing-prongs adapted to lie in the groove and projecting beyond the tube as and for the purpose specified.

In testimony whereof I have signed my 80 name to this specification in the presence of two subscribing witnesses:

LEWIS CREW FISHER.
